UNITED STATES PATENT OFFICE.

JOHN F. STANDISH, OF WINTHROP, MASSACHUSETTS, ASSIGNOR TO UNITED SHOE MACHINERY COMPANY, OF PATERSON, NEW JERSEY, A CORPORATION OF NEW JERSEY.

HEEL.

1,196,608

Specification of Letters Patent. Patented Aug. 29, 1916.

Application filed January 19, 1915. Serial No. 3,173.

To all whom it may concern:

Be it known that I, JOHN F. STANDISH, a citizen of the United States, residing at Winthrop, in the county of Suffolk and 5 State of Massachusetts, have invented certain Improvements in Heels, of which the following description, in connection with the accompanying drawings, is a specification, like reference characters on the drawings 10 indicating like parts in the several figures.

The object of this invention is to produce a cushion heel which may be attached without difficulty to a shoe, by the use of any 15 of the ordinary types of heel attaching machines.

Heretofore, cushion heels of soft material, such, for example, as rubber have, for certain reasons, been attached to shoes almost 20 universally by hand. It is customary to embed in such heels, in the process of their manufacture, flat metal washers, through which the attaching nails are driven. This is considered necessary for two principal 25 reasons; first, such heels are more or less soft and yielding in character and nails driven through them in the ordinary manner of attaching leather heels are liable to work up into the shoe after the cushion heel 30 is worn down sufficiently to permit the nail heads to come into engagement with the pavement under the pressure of the weight of the wearer; second, in many heels of this type, the nails will not hold but will pull 35 through, allowing the heel to become loose and drop off. It is apparent that the nails must be inserted with great accuracy, to insure that they will pass through the holes in the washers. This might be accomplished 40 by the heelng machine, if heels were all exactly alike; but different manufacturers space the washers differently and even the heels produced by one manufacturer are different in this respect, on account of slight 45 variations in the molds in which the heels are made and variations in the shrinkage of the rubber or other composition during the process of making the heels. The result of these variations in the location of the washers is that, when a gang of nails is driven into the heel by a heelng machine, in which they are guided through a nailing die by 50 holes having a fixed location and relation, a nail frequently strikes one of the washers.

This causes the nail to be deflected from its proper path with consequent failure of that nail to enter the shoe properly and to effect its attaching function securely. Furthermore, since the nails are usually driven near the edge of the heel, the point of a deflected 60 nail often emerges from the side of the heel, necessitating its removal and the attachment of a new heel. Attempts have been made to overcome these difficulties by vulcanizing sheets of canvas, or other material, into heels 65 to prevent the nails from working up into the shoe or pulling through the heels, but they have not met with commercial success for various reasons, one of the most important of which is that a sheet of inextensible 70 material in a heel destroys its resiliency or "life" by preventing it from expanding and contracting freely under pressure.

It is highly desirable that the natural 75 resiliency of a cushion heel shall not be impaired, and that the heel be adapted to be handled easily by machinery. In order to be successfully handled in heelng machines under commercial conditions, all heels of a given size and style must be capable of attachment without difficulty or waste and without the necessity of changing the adjustments of the machine. To satisfy these requirements is the primary object of this 80 invention.

In its general construction the heel of this 85 invention includes a plurality of nail guiding and holding members which are separate from and independent of each other, so that the resiliency of the heel is not impaired 90 by their presence in it, and the said members are constructed and arranged to insure that the nails shall be so guided as to perform their functions properly, even though the guiding and holding members may not be 95 located in the heel with great exactness.

In the preferred embodiment of the invention, a number of metallic inserts, corresponding to the number of nails to be used to attach the heel, are embedded in the heel. 100 Each of these inserts is preferably in the form of a dished washer which flares upwardly and outwardly from a central hole of approximately the size of the shank of the attaching nail. By reason of this formation, the point of a nail striking the washer at any place is guided toward the central hole and caused to pass properly there- 105

through. By this means considerable variation in the location of the washers in the heel may occur, and yet, the nails will all be guided so as to pass through the work properly and hold the heel securely in attached position.

From another point of view the invention comprises a nail guiding and holding device or insert adapted for use in cushion heels, 10 formed substantially as a frustum of a cone, or the equivalent thereof. In the specific embodiment of the invention, herein described and illustrated, the inserts or washers are shown as somewhat funnel-shaped or 15 in the form of a hollow, inverted, truncated cone, although it should be understood that the exact form shown is not essential to the success of the invention, but that other equivalent forms might be substituted, without 20 sacrificing the results and advantages to be attained.

In the drawings, Figure 1 is a perspective view showing a heel with a portion broken away to illustrate the invention clearly; Fig. 2 is a sectional view, upon an enlarged scale, of a detail of a heel embodying the invention, showing the manner in which a nail often strikes the washer; Fig. 3 is a view similar to Fig. 2 showing the manner in 30 which the nail is guided into proper position; Figs. 4 and 5 are similar views of a portion of a heel provided with the ordinary flat washer, showing how a nail strikes the washer and is deflected from its 35 path; and Fig. 6 is a perspective view, upon an enlarged scale, of a washer constructed according to the invention.

The reference numeral 2 denotes a cushion heel which may consist of rubber or any 40 of the compositions commonly employed in such heels. Holes 4 are formed in the heel near its periphery and a nail holding and guiding washer 6 is embedded in the substance of the heel at or near the bottom of each hole. The washers 6 are entirely separate from and independent of each other, so that they have no tendency to impair the "life" or resiliency of the heel by restricting in any way its expansion or contraction under pressure. The form of washer illustrated in Figs. 1, 2, 3 and 6 has been found very effective and satisfactory in practice. It is conveniently formed from sheet metal by a simple punching operation and is 50 dished in its top surface, as shown clearly at 8. A small flange 10 at the outer periphery of the washer affords additional holding power in the material of the heel and a slight projection 12 struck downwardly from the center of the washer makes its interior form such as to facilitate easy guiding of the nail 14 when the latter passes through the washer. The central hole 16 in the washer preferably approximates the diameter of the body of the nail 14, so that the

head of the nail is held securely from pulling through the washer, while the diameter of the periphery is preferably several times the diameter of the nail, in order that the washer may be certain to be struck by the 70 point of the nail, even though the washer be not located, or the nail be not driven, with great exactness.

When attaching a heel embodying this invention with a heelng machine, the nail guiding holes in the nailing die of which bear fixed relation to each other, it may frequently happen that the point of each nail will not initially enter exactly the hole in the washer, but the nail may strike the metal of 80 the washer, as indicated in Fig. 2. This is particularly likely to happen where headed nails are used, as is customary in rubber heel attaching, the points of which nails cannot always be guided with exactness in the nail 85 block, where the holes are necessarily large enough to pass the heads of the nails; and it frequently happens, also, when the washers may not be so located that their holes register accurately with the holes in the nail 90 block. Attempts to attach ordinary cushion heels commercially in this way have been unsuccessful for reasons which will be clearly apparent from an inspection of Figs. 4 and 5. When the point of a nail strikes 95 an ordinary flat washer, as shown at 18 in Fig. 4, the tendency, instead of being for the point of the nail to go toward the center of the washer, is to tip the washer, deflecting the nail entirely outside of the latter, as 100 shown clearly in Fig. 5. Under these conditions the nail is usually deflected sufficiently to prevent it from performing its attaching function properly, and frequently it is even turned so far from its path as 105 to cause it to emerge from the side of the heel. This, of course, necessitates the removal of the heel and the attachment of a new heel. The point of the nail is usually guided somewhat by the wall of the hole 4, 110 which is formed in the process of molding the heel, and the tendency of the nail point to strike the washer is aggravated by the fact that the hole 4 is always larger than the hole in the washer, thus leaving a sort of 115 shoulder at the bottom of the hole for the point of the nail to catch upon. This condition is due to the shoulder upon the pin in the mold, upon which the washer rests when the heel is formed around it. When, however, the washer of my invention is used, the point of the nail, when it strikes the metal of the washer, is positively guided toward the central hole in the washer and cannot escape passing therethrough. This device 120 in the heel, therefore, instead of being an impediment to the proper guiding and insertion of the nail, becomes a very material aid to that operation.

The washer of my invention may be 125

manufactured as easily and cheaply as an ordinary flat washer, and may be handled without difficulty in the usual manner in the process of manufacturing the heel. No disadvantages whatever result from its use, but, on the other hand, the incorporation of this invention in a cushion heel makes it possible to attach the heel by machinery with uniform success, a thing which has been entirely impracticable prior to the introduction of the invention. Its great importance may be appreciated when it is realized that heretofore it has been necessary to attach heels of this type by hand, whereas, by now making it possible to attach them by machinery, an enormous saving in labor is secured. This is a matter of material significance when large numbers of cushion heels are to be attached to shoes during the process of their manufacture, as is the case in many shoe factories today.

While the washer herein shown is approximately frusto-conical in shape, it is not essential that this exact form be preserved, since the advantages of the invention might be realized with other equivalent forms, such for example, as the frustum of a pyramid or the like. It is essential, however, that the side of the device which faces toward the approaching point of the nail, be of such formation as to guide the nail toward the central hole in the washer and to insure that the nail shall pass through the hole properly without being deflected from its path, and without displacing the washer from its position in the heel.

Having fully described my invention, what I claim as new, and desire to secure by Letters Patent is:—

40 1. A rubber heel having a plurality of separate spaced-apart nail-engaging washers embedded in its body, said washers being provided with dished sides extending from the marginal portions of the washers 45 to the rims of the nail-receiving apertures therein and facing the tread surface of the heel, said washers constituting independent nail-deflecting guides, which are isolated

from each other by resilient portions of the heel body. 50

2. A cushion heel having embedded therein a plurality of separate and independent nail guiding inserts, each of said inserts having a surface so disposed as to guide the point of a nail toward its center. 55

3. A cushion heel having embedded therein a plurality of separate and independent nail guiding inserts, each of said inserts having a surface so disposed as to guide the point of a nail toward its center, and having a marginal flange arranged to resist displacement of the insert from its position in the heel. 60

4. A cushion heel having embedded therein a plurality of separate and independent metallic inserts, each of said inserts being in the form of a dished washer flaring upwardly and outwardly from a central hole. 65

5. A cushion heel having embedded in its body a nail engaging washer provided with 70 dished sides extending from the marginal portion of the washer to the rim of the nail receiving aperture therein and facing the tread surface of the heel, and with a narrow marginal flange of a width sufficient to resist displacement of the washer from its position in the heel while leaving the resiliency of the heel unimpaired. 75

6. A rubber heel having a plurality of separate spaced apart nail engaging washers embedded in its body, said washers being provided with dished sides extending from the marginal portions of the washers to the rims of the nail receiving apertures 80 therein and facing the tread surface of the 85 heel, and with marginal flanges arranged to resist displacement of the washers from their positions in the heel. 90

In testimony whereof I have signed my name to this specification in the presence of two subscribing witnesses.

JOHN F. STANDISH.
